(57) **CLAIM**

The ornamental design for a set of overhead racks, as and described.

DESCRIPTION

FIG. 1 is a perspective view of a set of overhead racks showing my new design;

FIG. 2 is a front perspective view showing a single rack thereof, removed from the set for clarity of disclosure;

FIG. 3 is a rear perspective view thereof;

FIG. 4 is an enlarged rear perspective view thereof;

FIG. 5 is a front elevational view thereof;

FIG. 6 is a rear elevational view thereof;

FIG. 7 is a right side view, the left side being a mirror image thereof;

FIG. 8 is a top view thereof; and,

FIG. 9 is a bottom view thereof.

The subject matter illustrated in broken lines forms no part of the claimed invention.
